NECKTIE

Alfred F. Tatarski, Buffalo, N. Y.

Application August 19, 1944, Serial No. 550,255

9. Claims. (Cl. 2—150)

1

This invention relates to articles which may be used in place of neckties, which have the appearance of neckties, and therefore have for convenience been referred to as neckties. These necktie substitutes may be of the four-in-hand style or the bow-tie style. Heretofore, when one desires to wear different ties on different days to avoid monotony, it is necessary to obtain a substantial number of different complete ties which requires a substantial investment and limits the range of color and visual effects that some people desire.

An object of this invention is to provide an improved tie to be worn at the collar of a man's shirt, which may be easily attached to, or detached from, the shirt at the neck, with which a wide variety of color and pattern combinations of appearance may be obtained with a minimum number of parts, with which a person's individual choice may be expressed in various combinations, and which will be relatively simple, practical, and inexpensive.

Another object of the invention is to provide an improved, pre-formed tie for attachment to men's shirts at the neck band, which may either be hooked over the collar button or equivalent device that connects the neck band ends together, or secured to the neck band by a ribbon-like strip which extends around the neck band and is coupled to the tie.

Another object of the invention is to provide an improved, pre-formed tie which eliminates the necessity of tying it each time it is worn, which will have the same general decorative effect as the ordinary tie, with which combinations of designs, colors and patterns may be obtained on the knot portion of the tie, and in the streamers or panels that depend from the knot portion, with which the improved tie may be assembled or made up of different parts in different combinations in a simple manner to produce different visual effects.

Another object of the invention is to provide an improved shield for application over the knot portion of a tie for protecting the knot portion from soiling, and to give different color and visual effects thereto.

Another object of the invention is to provide an improved, pre-formed tie substitute which is formed of a plurality of parts or sections that may be easily and quickly assembled in different combinations to produce different visual effects.

Other objects and advantages will be apparent from the following descriptions of several embodiments of the invention, and the novel features

2

will be particularly pointed out hereinafter in connection with the appended claims.

In the accompanying drawing:

Fig. 1 is a side elevation of a pre-formed tie substitute, constructed in accordance with this invention but with the fabric portions shown only by dash lines;

Fig. 2 is a rear elevation of the same;

Fig. 3 is a sectional plan of a portion of the same, the section being taken approximately along the line 3—3 of Fig. 1;

Fig. 4 is a perspective of the form constituting the knot portion of the tie having a different way of connecting thereto the securing band which encircles the shirt at the neck;

Fig. 5 is a view similar to Fig. 4 but illustrating a different type of construction by which the neck encircling strip may be attached to the form of the tie;

Fig. 6 is a side elevation similar to Fig. 1, but illustrating a slight modification thereof, in which the sections of the knot part of the form have clamped between them a ring, shown in section, which provides a decorative effect and a convenient way of securing the edges of the enclosing fabric at the junction between the sections;

Fig. 7 is a longitudinal, sectional elevation through a portion of the knot part of this tie, such as shown in Fig. 6, and illustrating one simple and practical manner of connecting the sections together;

Fig. 8 is a longitudinal, sectional elevation of a tie such as shown in Fig. 1, but illustrating a modified construction for attaching the streamers to the knot portion, and also illustrating another manner in which the sections of the form may be detachably coupled;

Fig. 9 is a perspective of the knot portion of a tie having a shield attached thereto to protect the knot portion and to provide a desired visual effect;

Fig. 10 is a sectional plan of the same, with the section taken approximately along the line 10—10 of Fig. 9;

Fig. 11 is a view similar to Fig. 9, but illustrating a different type of shield and a different type of connection between the shield and the knot portion of the tie; and

Fig. 12 is a sectional elevation of the lower part of the knot section 12 and attachment means for a streamer, and illustrating another embodiment of the invention.

In the embodiment of the invention illustrated in Figs. 1 to 3, the tie has much of the appearance of an ordinary four-in-hand style of tie,

but instead of a single strip of fabric which encircles the neck and then has its ends tied to form a knot, the improved tie or tie substitute is formed quite differently. This embodiment of the invention includes a body or form 10 having approximately the shape of the knot portion of the ordinary tie, transversely divided into a plurality of detachably connected sections 11 and 12. The form 10 is provided, in its upper section, with a pair of recesses 13 opening into the same from the rear and receiving individually the arms 14 of a U-shaped member 15. The arms 14 of this U-shaped member are preferably formed to engage the walls of the recesses 13, so as to be frictionally or yieldingly held therein, and for this purpose, the arms 14 may be transversely corrugated so that their effective thickness is slightly greater than the thickness or width of each recess 13, so that when an arm 14 is forced into its related recess 13, the walls of the recess will tend to flatten out the corrugations and provide sufficient frictional pressure to detachably connect the member 15 to the form 10.

This member 15, when attached to the form 10, has its projecting portion bent upwardly as shown in Figs. 1 and 2 with the cross part of the U at the top. This makes it possible to push the upstanding portion of the U downwardly over a collar button of a shirt, or the button which connects the ends of the neck band together in the case of a shirt having an attached collar. The upstanding portion of the member 15 is also provided with laterally extending eyes 16 to which the ends of a strip or band 17 may be detachably connected, the band 17 being shown only by dash lines in Fig. 2 since it, per se, is not a part of this invention. Usually the strip or band 17 is made of entirely elastic material or of other material with an elastic section.

The lower end or portion of the lower section 12 is provided with a reduced neck 18 to enable attachment thereto of one or more panels or streamers of the tie. Relatively rigid members 19 and 20 are provided with spring lamp arms 21 and 22 respectively, which telescopingly engage over each other and over the neck 18 of the form section 12. For example, the clamp arms 22 may first be snapped over the neck 18 and then the clamp arms 21 may be snapped over the arms 22, as shown in Fig. 3. The clamp arms 21 and 22 extend more than halfway around the neck 18, so as to normally remain attached thereto, but which may be removed therefrom by springing them apart.

Each of the members 19 and 20 has a depending web portion 23 with apertures 24 therein, to which the upper end of the streamers or panels of textile fabric or other similar sheet materials are secured. This textile fabric or sheet material forming the streamers is shown by the dash lines 25 in Figs. 1 and 2 and full lines in Figs. 6, 8, 9 and 11. There are two members, 19 and 20, so that two panels or streamers 25 may be used to simulate two streamers or panels of an ordinary four-in-hand tie. The fabric or sheet material 25 forming the panels preferably extends at least to the upper edge of the clamp arms 21 and 22 to conceal them. Sections 11 and 12 of the form may be individually covered by textile fabric or other covering material 26 shown in dash lines in Figs. 1 and 2 and in full lines in Figs. 6 and 7, the fabric being formed separately for the two sections in Figs. 1 to 4 and the edges where the sections abut are disposed between the

abutting faces, so as to be concealed and clamped between the sections.

The sections 11 and 12 may be detachably coupled in any suitable manner, and the sections 5 11 and 12 may be covered with different textile fabrics of different colors and patterns, to produce different visual effects, or the sections 11 and 12 may be formed as highly decorative plastics or other materials which may be covered or 10 not, as desired. In place of the U-shaped device 15, by which the form may be attached to the neck portion of the shirt, separate eyes 16a may be attached to the upper section 11 of the form 10, as shown in Fig. 4, and the band or strip 15 17 detachably connected thereto. In place of either of these means for attaching the form 10 to the neck portion of the shirt, a jacket 27, Fig. 5, knitted of textile material or other elastic material may be fitted over the form 10 so as to 20 fit snugly thereto and conform to its shape, and this jacket may carry eyes 28 on the rear face into which may be hooked the ends of the band 17. This jacket 27 may be tailored from sheet material to fit the form 10, but preferably it is 25 made of knitted material with a type of elastic mesh which enables the jacket to stretch for application over the form 10, and, when released, resiliently contract over and fit the form 10.

In some instances it may be desirable to 30 separate the sections with a decorative ring 29 (Fig. 6). In this embodiment of the invention, the fabric 26 is shown in full lines as applied over the form, and the means by which the tie may be attached to the band 17 illustrated as eyes 16a 35 of the type shown in Fig. 4. The streamers 25 are shown in full lines. In this embodiment of the invention which is also shown in section in Fig. 7, the ring 29 is a closed, circular ring, whose internal diameter is slightly less than the external diameter of the form 10, and the abutting faces of the sections 11 and 12 may be slightly beveled or grooved at the peripheral edges of their abutting faces so as to fit the surface of the ring 29. The edges of the covering 26 are confined beneath the ring 29, as shown in Fig. 7.

While any means may be employed for detachably coupling the sections 11 and 12, a practical construction for that purpose is illustrated in Fig. 7. In accordance with this construction, 50 the abutting faces of the sections 11 and 12 are provided with aligned, cylindrical recesses 30 and 31, and a cylindrical sleeve 32 is frictionally and telescopically fitted within, and against the outside or peripheral wall of, the recess 30 and extends outwardly beyond the face of section 12 which abuts section 11. A metal liner 33 fits the peripheral wall of the recess 31 in section 11, and the inside diameter of this liner 33 is approximately the same as the outside periphery of the 55 sleeve 32. The sleeve 32 is cemented or otherwise secured to the section 12, and the liner 33 is cemented or otherwise secured to the section 11. The projecting end of the sleeve 32 is provided with longitudinal slits 34 which divide the projecting portion into spring fingers having inwardly turned flanges 35 so that when the sections 11 and 12 are brought together in aligned relationship, the fingers in the projecting portion of the 60 sleeve 32 will be sprung inwardly slightly as they are inserted within liner 33 and will frictionally engage and slide along the liner 33. This provides a frictional action between them which will resist separation and relative rotation of the sections 11 and 12. The sleeve 32 thus aligns 65

the sections 11 and 12 and frictionally couples them.

Additional means is also preferably provided to prevent unintentional separation of the sections 11 and 12 and for this purpose, a screw 36 (Fig. 7) is threaded at its opposite ends into bosses 37 and 38 projecting from the bottom walls of the recesses of the sections 11 and 12 respectively. By relative rotation of the sections 11 and 12, disengagement of the screw 36 from one of the sections may be obtained, whereupon the sections may be separated, but the frictional engagement of the slotted end of the sleeve 32 with the liner 33 resists accidental or unintentional relative rotation of sections 11 and 12 that would tend to separate them.

In Fig. 8 a slight modification in the manner of coupling the sections 11 and 12 is illustrated. In this example, the section 11 has a cavity or recess 39 opening through its outer end and closed by a cover 40 hinged at 41 and spring pressed into closed position. Its free edge 42 has an internal lip making a snap engagement with the adjacent wall-edge portion 43 or the recess opening, and that edge portion is slit at its ends as at 44 (only one slit being shown) so that the wall section 43, which has latched engagement with the edge 42, can be pressed inwardly to release the cover 40. A screw 45 with its head in the recess 39 is threaded through the bottom wall of recess 39 into the other section 12.

In this embodiment of the invention, the sections 11 and 12 also have telescoping, interfitting parts, concentric with the peripheries of the sections 11 and 12, to position the sections relatively to one another and for this purpose the section 12 has a cylindrical recess 46 in its end face which abuts the section 11, and the abutting end face of the section 11 has a projecting, cylindrical boss 47 which telescopes into, and rotatably fits the recess 46. The screw 45 passes through the boss 47 into section 12. In this embodiment of the invention, the streamers 25 are connected to members 19 and 20 that are similar to the members 19 and 20 of Figs. 1 and 2, except that here, the spring arms 21 and 22 are pressed toward one another and inserted into a recess 48 in the lower end of the section 12 in telescopic arrangement with respect to each other and to recess 48, and the outward expansion of the released spring arms causes the arms to grip the peripheral wall of the recess 48 and secure the streamers 25 in place. The inner portion of the peripheral wall of the recess 48 may have a slightly greater diameter than the entrance to the recess, so that the slight undercut in the recess wall, thus provided, will aid in preventing accidental or unintentional movement of the spring arms 21 and 22 from the recess 48.

In Fig. 12, a further modification is shown in which the section 12 has a recess 49 in its lower end provided with slits 50 so as to provide spring fingers from the side walls of the recess. The streamers 25 are connected to a common member 51 which has a head 52 that is inserted into the recess 49. This member 51 has an annular groove or undercut portion 53 at the base of the head into which the outer ends of the fingers, formed by the slots 50, may snap to lock the head 52 within the recess 49. The fingers yield, however, when sufficient outward pull is placed on the member 51 to permit removal of the head 52. The bottom of the recess 49 is provided with a smaller recess 54. The head 52 is provided with a pin 55 that telescopes into and fits the

recess 54, so as to serve as a locating means and to prevent lateral rocking movement of the member 51.

It is sometimes desirable to protect from soiling the knot portion of a tie of the ordinary four-in-hand type or of the knot portion of the tie substitute shown in Figs. 1 to 8, and for this purpose I have provided a shield 56 of resilient material, preferably transparent, which has a shape in cross section of slightly more than half circle, so that by springing the arms apart, the shield 56 may be snapped over the knot portion or form 10 of a tie, and it will be frictionally confined thereon. The shield 56 may have any desired color or design, or both, and a plurality of such shields may be provided of different colors, shapes and designs on their outer surfaces, so that one may change the appearance of the same tie by applying different shields thereover on different days, as the wearer may desire. The embodiment shown in Fig. 11 is similar, except that the shield 57, which corresponds to the shield 56, instead of being formed to spring over the knot portion or form 10 of the tie, merely embraces it and is secured thereto by a snap fastener 58, one part of which is carried by the shield 57, and the other part of which is carried by the knot portion or form 10 of the tie. In Figs. 9, 10, and 11, the knot part 10 may be the knot of the ordinary four-in-hand tie, or it may be the form element 10 of Figs. 1 to 8.

In Figs. 1 to 8 and 12, it will be observed that the form is transversely divided into two sections which have telescoping parts by which they may be properly assembled, with coupling means between them, and by using or omitting the ring 29, different visual effects may be obtained. By making the various parts of the tie of different colors and materials, or by using different fabric coverings for the various parts, and as the streamers 25, a large variety of different, attractive tie combinations can be obtained with a very few parts.

Various other ways of coupling the sections 11 and 12 together, and the streamers to the knot portion can be provided within the broadest concept of the invention.

It will be understood that various changes in the details, materials, and arrangements of parts, which have been herein described and illustrated in order to explain the nature of the invention, may be made by those skilled in the art within the principle and scope of the invention, as expressed in the appended claims.

I claim as my invention:

1. A necktie comprising a form having approximately the shape of the knot part of a tie, and transversely divided into a plurality of sections, said sections having detachable, interconnecting parts at their abutting faces, within the periphery of the sections at said faces, one of said sections carrying means by which it may be removably supported at the front of the neck band, and a streamer part detachably coupled to and depending from the lowest section of said form.

2. A necktie comprising a form having approximately the shape of the knot part of a tie, and transversely divided into a plurality of sections, said sections having detachable, interconnecting parts at their abutting faces, within the periphery of the sections at said faces, one of said sections carrying means by which it may be removably supported at the front of the neck band, a streamer part detachably coupled to and

depending from the lowest section of said form, and a concentric ring interposed between said sections at the peripheries of their abutting faces.

3. A necktie comprising a form having approximately the shape of the knot part of a tie, and transversely divided into a plurality of sections, said sections having detachable, interconnecting parts at their abutting faces, within the periphery of the sections at said faces, one of said sections carrying means by which it may be removably supported at the front of the neck band, a streamer part detachably coupled to and depending from the lowest section of said form, and a concentric ring interposed between said sections at the peripheries of their abutting faces, said sections being individually covered with a textile fabric, whereby by using a ring with any of selected colors, and fabrics and streamers of different colors and patterns, a relatively wide variety of visual effects for the tie can be selectively obtained.

4. A necktie comprising a form having approximately the shape of the knot part of a tie, and transversely divided into a plurality of sections, said sections having telescoping portions for connecting the sections and holding them in alignment.

5. In a preformed necktie of the type having a form approximately of the shape of the knot part of a tie, and a streamer part coupled to, and depending from, the lower portion of said form, that improvement in said form which comprises a body divided transversely into a plurality of sections, said sections having telescoping and interfitting portions for aligning the sections with respect to one another, and holding them against separation and additional means within the body and detachably coupling the sections together.

6. In a preformed necktie of the type having a form approximately of the shape of the knot part of a tie, and a streamer part coupled to, and depending from, the lower portion of said form, that improvement in said form which comprises a body divided transversely into a plurality of sections, said sections having telescoping and interfitting portions for positioning the sections with respect to one another, one of said sections having a cavity therein and a coupling member accessible through said cavity for coupling and uncoupling said sections.

7. In a preformed necktie of the type having a form approximately of the shape of the knot part of a tie, and a streamer part coupled to, and depending from, the lower portion of said form, that improvement in said form which comprises a body divided transversely into a plurality of sections having telescoping and interfitting portions for positioning the sections with respect to one another, one of said sections having a cavity therein and a coupling member accessible through said cavity for coupling and uncoupling said sections.

one another, one of said sections having a cavity therein, and a coupling member accessible through said cavity for coupling and uncoupling said sections, said section with said recess having a movable closure normally closing the cavity but opening to enable access to said coupling member.

8. In a preformed necktie of the type having a form approximately of the shape of the knot part of a tie, and a streamer part coupled to, and depending from, the lower portion of said form, that improvement in said form which comprises a body divided transversely into a plurality of sections, said sections having telescoping and interfitting portions for positioning the sections with respect to one another and a ring disposed between said sections at their abutting faces and concentric with said form, said ring having a smaller internal diameter than the outside diameter of said body at the abutting faces of the sections, whereby said ring may be clamped between said sections.

9. In a preformed necktie of the type having a form approximately of the shape of the knot part of a tie, and a streamer part coupled to, and depending from, the lower portion of said form, that improvement in said form which comprises a body divided transversely into a plurality of sections, said sections having telescoping and interfitting portions for positioning the sections with respect to one another, a ring disposed between said sections at their abutting faces and concentric with said form, said ring having a smaller internal diameter than the outside diameter of said form at the abutting faces of the sections, whereby said ring may be clamped between said sections by assembling said sections, and a covering of textile fabric for each section, with the edges of the covering at said ring clamped beneath the ring to the section, whereby the ring will conceal the free edges of the covering at the joint between the sections.
